(57) **CLAIM**

We claim the ornamental design for a stand for electronic device, as shown and described.

DESCRIPTION

FIG. 1 is a front perspective view of a stand for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view in which a display panel is provided in broken lines to illustrate an example environment; and,

FIG. 9 is another right-side view of the stand for electronic device shown in an alternate position in which a display panel is provided in broken lines to illustrate an example environment.

The broken lines in FIGS. 1-7 illustrate portions of the stand for electronic device that form no part of the claimed design. The broken lines illustrating the display panel in FIGS. 8 and 9 are environment, while the remaining broken lines in
